(57) **CLAIM**

The ornamental design for an amp rack and fuse holder base,
as shown and described.

DESCRIPTION

FIG. 1 is a top perspective view of an amp rack and fuse
holder base, showing my new design with amps, fuses, and
other components attached thereto in a condition of use;
FIG. 2 is an exploded top perspective view thereof with the
components omitted;

FIG. 3 is an exploded bottom perspective view of FIG. 2;
FIG. 4 is a top perspective view of FIG. 1 with the
components omitted;

FIG. 5 is a bottom perspective view of FIG. 4;

FIG. 6 is a front elevational view of FIG. 4;

FIG. 7 is a rear elevational view of FIG. 4;

FIG. 8 is a left-side elevational view of FIG. 4;

FIG. 9 is a right-side elevational view of FIG. 4;

FIG. 10 is a top plan view of FIG. 4; and,

FIG. 11 is a bottom plan view of FIG. 4.

The broken lines showing various components depict envi-
ronmental matter and form no part of the claimed design.
The remaining broken lines in the figures depict portions of
the amp rack and fuse holder base that form no part of the
claimed design.
